UNITED STATES PATENT OFFICE.

TULLY W. BENSON, OF WINKELMAN, ARIZONA.

ROTARY ENGINE.

1,106,617.

Specification of Letters Patent. Patented Aug. 11, 1914.

Application filed June 3, 1913. Serial No. 771,563.

To all whom it may concern:

Be it known that I, TULLY W. BENSON, citizen of the United States, residing at Winkelman, in the county of Gila and State 5 of Arizona, have invented certain new and useful Improvements in Rotary Engines, of which the following is a specification.

My invention relates to rotary engines and particularly to that type of engine in 10 which a bladed rotor is used, and in which the motive fluid is admitted continuously behind each blade or piston of the rotor during nearly the whole of the rotation of the rotor and exhausted from in front of 15 each piston or blade during nearly the entire rotation of the rotor.

The primary object of my invention is the provision of a rotary engine of an effective character and exceedingly simple construction, having few parts and therefore little liable to get out of order and in which friction between moving parts is reduced to a minimum.

A further object in this connection is to 25 provide a rotatable cylinder within which the rotor is mounted and with which it moves whereby to eliminate friction between the rotor blade and the exterior cylinder.

A further object is to so construct the 30 rotor blade and the part supporting it that the rotor blade may be readily shifted entirely within the circumference of the rotor at the point where the rotor comes in contact with the outer cylinder to thus provide 35 for a fluid tight joint between the rotor and cylinder at this point.

A further object is to provide means 40 whereby steam may be taken into the space behind the piston between the rotor and the cylinder during a certain extent of rotation without the necessity of providing more or less complicated cut-off valves for this purpose.

A further object is to provide a construction 45 which shall particularly adapt the rotary engine for use as a compound engine in which the exhausted motive fluid is carried from the high pressure rotor to the low pressure rotor.

A further object is to provide means 50 whereby the rotatable cylinder inclosing the rotor and the rotor itself shall be independently journaled so that one may be adjusted with relation to the other to secure a proper operation of the parts.

A further object is to provide means for

packing the rotor with relation to the inclosing cylinder, the cylinder and rotor moving together so that this packing will practically have no wear.

Other objects will appear in the course of the following description.

My invention is illustrated in the accompanying drawings wherein:

In the drawings: Figure 1 is a longitudinal section of a rotary engine constructed in accordance with my invention, the section being taken on the line 1—1 of Fig. 2; Fig. 2 is a section on the line 2—2 of Fig. 1; Fig. 3 is a perspective view of the rotor and 60 the rotor blades, the blades being separated from the rotor. Fig. 4 is a sectional detail illustrating the manner of pivoting the segmental piston head to the casing.

Corresponding and like parts are referred 65 to in the following description and indicated in all the views of the accompanying drawings by the same reference characters.

Referring to these drawings, 2 designates a base of any suitable construction upon 70 which the engine is mounted and having the pillars 3 carrying shaft bearings 4 at their upper ends. Disposed in these bearings is a shaft 5 adapted to be driven by the rotor.

Mounted upon the base 2 is a casing composed of the end pieces 6, the side sections 7 and the top section 8. The sections are bolted or otherwise attached to each other in any suitable manner. The end members 6 are annular in form to permit the passage 75 of the shaft 5. Bolted or otherwise attached to each of the end members is a plate 9 which has an inwardly projecting circular hub 9^a less in diameter than the diameter of the opening through the adjacent end member 80 6. The particular construction of these plates 9 and their use will be apparent later.

Mounted upon the shaft 5 and within the casing is a rotor 10. As illustrated, this rotor is adapted to be used with a compound 85 engine and is therefore formed in two sections but this form of construction will be referred to later. The rotor is circular in form as illustrated in Fig. 3. The rotor is hollow and is keyed or otherwise fastened 90 upon the shaft 5. This rotor is provided 95 with a radially shiftable blade.

Surrounding the rotor is a cylinder 11, the inner surface of which is eccentric to the peripheral surface of the rotor so that the 100 rotor and the inner face of the cylinder touch at the point *a*, Fig. 2. The cylinder 110

11 has a width equal to the width of the rotor and each end of the cylinder is closed by an annular plate 12 which may be bolted to the cylinder 11. Each plate 12 has a projecting annular hub 13 formed at its end. The extremity of the hub has at its end a bearing ring 14 and the edge of this ring is formed with a raceway engaging the ball bearings 15. The outer circumference of the hub 9^a of the plate 9 has a diameter equal to the interior diameter of each hub 13 so that the hub 9^a fits within the hub 13.

It will be seen from Fig. 1 that the hub 9^a is bored eccentrically to its axis for the passage of the shaft 5 and that therefore while the cylinder 11 with its end walls 12 rotates concentrically to the axis of the hub 9^a, the axis of the rotor is eccentric to the axis of the hub 9^a and therefore eccentric to the axis 20 of cylinder 11. A packing ring 16 is disposed between the outer face of the hub 13 and the adjacent edge wall of the end piece 6, this edge wall of the end piece being preferably recessed to receive this packing. 25 This is the only packing which is needed between the cylinder and the casing within which it rotates. Preferably the rotor is also annularly recessed at each end to receive the packing rings 17 and preferably 30 the inner face of one of the end pieces 12 is recessed to receive packing 18 contacting with the end wall of the rotor.

It will be noticed from Fig. 2 that the outer face of the cylinder 11 is spaced from 35 the outer face of the casing formed by the sections 7 and 8, the base 2 and the end walls 6. The space 19 thus formed is designed to be filled with steam. The end walls 6 are 40 annularly cut away as at 20 so as to permit a certain very small amount of steam to leak into the space between the end walls 12 and the end walls 6 and thus reduce friction between the end walls of the cylinder and the end walls of the casing. The rotor is 45 provided at one point in its circumference with a slot 21, this slot extending the entire length of the rotor, and the rotor is also formed with a plurality of slots 22 extending circumferentially. Each of these slots 50 at the end farthest from the blade-receiving slot 21 is relatively shallow and the bottom of the slot extends in a curve from this point to the bottom of the slot 21. Pivotally mounted in the slots 22 are the arms 23 carrying at their ends the transversely extending blade 24. This blade constitutes a 55 piston head and may be made in any suitable manner but as shown is recessed around its edge for the reception of packing 25. 60 The slot 21 is struck upon a curve concentric to the pivotal axis of the arms 23 and the head or blade 24 has the same curvature as the curvature of the slot 21. The slot 21 is 65 of such depth that when the blade 24 is moved all the way into the slot, the outer

edge of the blade will be flush with the periphery of the rotor. The outer edges of the arms 23 also have a curvature of the same degree as the inside of the cylinder 11 so that when the blade is moved all the way 70 into the recess 21, the upper edges of the arms 23 will lie flush with the inside face of the cylinder. While I have illustrated two of these arms for the rotor, I do not wish to be limited to this number as a more or less 75 number of these arms might be used. The upper edge of the blade is pivotally connected at its corner to the cylinder 11. This pivotal means may be of any character but I have shown it as an ear 26 projecting from the inner face of the cylinder into a slot 26^a in the edge of the rotor blade, there being a pin 26^b passing through this slot and through the ear. Inasmuch as the rotor is eccentric to the inner periphery of the cylinder, it is 80 obvious that as the cylinder and rotor rotate together in the direction of the arrow, Fig. 2, the surface of the cylinder and rotor will come gradually nearer and nearer together and the blade will gradually go farther and 85 farther into the slot 21 until the point of contact between the rotor and cylinder is passed, whereupon the adjacent surface of the rotor and cylinder gradually separate and the blade is drawn out. At the 90 point diametrically opposite the point of contact of the blade and cylinder, the blade is drawn out to its fullest extent. Immediately behind the blade is an inlet 95 port 27 passing through the wall of the cylinder 11 and into the fluid space 19. It will be seen that as this fluid space extends entirely around the cylinder 11, the port 27 will at all times be in communication with 100 this fluid space. The outer casing is also provided with a fluid inlet port connected by means of a duct 28 to a source of fluid under pressure. One or both end walls of the cylinder immediately in advance of the blade 24 is formed with an exhaust port 29. It is to be noted that both the exhaust port 105 and the inlet port 27 travel with the cylinder and that this cylinder travels with the rotor so that the exhaust port and the inlet port both have a fixed relation to the blade 24. Thus the port on one side of this blade is at 110 all times connected with the space behind the blade while the other port is at all times connected to the space in front of the blade. 115

The operation of the invention so far as 120 described is as follows. With the parts in position shown in Fig. 2, steam is entering through port 27 into the space A behind the blade and driving the blade forward. The space B between the front of the blade and the point of contact *a* is filled with exhaust steam or other motive fluid. As the blade 125 travels forward in the direction of arrow, Fig. 2, it is obvious that this space B will continually decrease in content and that the 130

exhausted fluid within the space B will be driven out through the port 29. As the blade passes the point α which constitutes an abutment, steam will enter between the 5 blade and this point of contact or abutment and will act to impel the blade forward. The space A behind the piston will gradually increase as the blade moves from the point α to its uppermost point of movement 10 so as to permit the steam or other motive fluid in the space 8 to expand. This expansion will continue throughout a complete revolution of the rotor, that is, until the exhaust opening 29 reaches and passes the 15 point of contact α . It is obvious that cut-off devices may be used for cutting off the inflow of steam into the space A at any desired point. A cut-off valve for this purpose being obvious, I have not shown it or 20 described it specifically. Where, however, steam is intended to enter through the entire rotation of the rotor, no cut-off valve is necessary.

I have heretofore described my rotary engine as if it were a simple engine, but in order to show that the principle of construction is equally adaptable to compound engines, I have illustrated the engine as compounded and as provided with a high 25 pressure rotor chamber designated C and a low pressure rotor chamber designated D. These chambers are separated by means of an annular partition 30 which is preferably attached to the cylinder 11 though not necessarily so and which is received in an annular recess 31 formed in the rotor. Where the engine is a compound engine, I preferably form the rotor in two sections, c and d , the section c being formed on its inner face 30 with a projecting hub 32 having a depth equal to the thickness of the partition 30. This section c is bolted to the section d by bolts 33. I do not wish to be limited to this construction however. Where the engine is 40 a compound engine, it is obvious that the exhaust opening 29^a leading from the rotor chamber C will be formed in the partition 30 and will extend rearward so as to open behind the blade as at 27^a in the low pressure 45 rotor chamber. It will further be seen of course that the exhaust port 29 for the chamber D will be disposed in advance of the blade of the rotor section d .

As illustrated and as I preferably construct by rotary engine, the end members 9 are annular in form so as to provide an annular portion 34 seating in an annular recess formed in the adjacent end plate 6 and bolted to this end plate by bolts 35. 50 This annular portion 34 is outwardly dished as at 36 so as to extend out over the extremity of the adjacent hub 13 and the inner face of this dished portion 36 is formed with a ball bearing race 37 and adapted to 55 coact with the antifriction balls 15. While

I have illustrated the arms 23 as attached to the blade 24 and the outer edge of the blade 24 as pivoted to the cylinder 11, I wish it distinctly understood that the rotor is to be considered as attached to the cylinder by 70 means of the arms and that these arms might be separate from the blade, though preferably the arms support the blade as well as form the means whereby the cylinder and rotor are connected.

For the purpose of providing for the exhaust of motive fluid from the low pressure cylinder D through the port 29, I provide an inner wall 38 which is disposed inside of the wall 12 at the low pressure end of the 75 cylinder and which may be formed with or attached to the peripheral wall 11 of the cylinder. The wall 38 is separated from the wall 12 by an exhaust space or duct 39 which leads to an exhaust port 40 in the portion 9^a of the end plate 9. This exhaust space 39 is in constant communication with the exhaust port so as to provide for the constant exhaust of motive fluid from the space in advance of the blade of the cylinder 80 D. As each piston and its arms are connected to the outer cylinder and to the rotor, it will be obvious that the blades will move out and in automatically but springs may be used beneath the blades to assist this 85 outward movement, and it will be further obvious that if the centrifugal force is too great, thus causing too great pressure against the cylinder, the arms and blade may be counterbalanced so as to reduce this 90 outward pressure.

It will be particularly noted that the blades of the high and low pressure cylinders of the rotor are in alinement with each other. This is for the reason that 100 during a revolution when the rotor ends of the arms 23 pass contact point α , the rotor and cylinder are traveling at exactly the same speed, but the instant the rotor ends of the arms 23 pass that point and begin to 105 move away from the cylinder 11, there is a change in the speed of travel between the cylinder 11 and the rotor. Hence if one piston blade should be disposed other than exactly in line with the other piston blade, 110 the engine would stop or brake. The bearings for the rotor shaft as well as the bearings for the hollow cylinder shaft 13 may be made adjustable to suit any requirement 115 such as adjusting the relative positions of the rotor and the cylinder. These bearings may be ball bearings, roller bearings or ordinary plain bearings.

While I have illustrated the division between the high pressure and low pressure 120 cylinders as formed by the partition 30, I wish it understood that it is within the scope of my invention to provide two entirely 125 separate rotors, each operating in an entirely separate rotor chamber, and that the 120

details illustrated and described are for the purpose of illustrating my invention and that I do not wish to be limited to these details. Neither do I wish to be limited to the 5 use of my invention in connection with any particular motive fluid as it is obvious that my rotary engine may be used with fluid in a state of compression or as an internal combustion motor.

10 What I claim is:

1. A rotary engine of the character described including an exterior casing, a hollow cylinder disposed within the casing and spaced therefrom and having an inlet port, 15 a rotor mounted within the cylinder and having a radially extending piston, and operative connections between the rotor and cylinder whereby they shall travel together.
2. A rotary engine including an outer 20 casing connected to a source of fluid pressure, a hollow cylinder rotatably mounted within the casing and having an inlet port communicating with the interior of the casing, a rotor mounted within the cylinder 25 and operatively connected thereto to travel therewith, and a radially movable blade carried upon the rotor.

3. A rotary engine of the character described including an outer casing, a hollow 30 cylinder rotatably mounted in the outer casing, a rotor mounted within the hollow cylinder, the rotor being eccentric to the interior face of the cylinder and touching said face at one point, and a radially movable 35 piston head coating with the rotor and the cylinder, the cylinder being provided with an inlet port behind the head communicating with the interior of the casing and with an exhaust port and the cylinder and rotor being operatively connected for coincident 40 rotation.

4. A rotary engine of the character described including an outer casing connected 45 to a source of fluid pressure, a cylinder rotatably mounted within the outer casing and having an inlet port opening thereinto and an outlet port, a rotor eccentrically mounted within the cylinder and contacting therewith at one point, a radially movable 50 blade carried upon the rotor and contacting with the inner face of the cylinder between the outlet and inlet ports, and operative connections between the rotor and cylinder whereby they shall rotate coincidentally.

5. A rotary engine of the character described including a hollow cylinder rotatably mounted and having an inlet port and an outlet port, a rotor eccentrically mounted within the cylinder and touching the interior face thereof at one point, a radially movable blade mounted upon the rotor and pivotally connected to the cylinder and disposed between the inlet and the outlet ports.

6. A rotary engine of the character described including a hollow cylinder rotatably

mounted, a rotor eccentrically mounted within the hollow cylinder and touching the latter at one point, a radially movable piston head mounted upon the rotor, and arms extending from the piston head and pivoted to the rotor, the outer edge of the piston head being pivotally connected to the cylinder, said cylinder being provided with an inlet port and an outlet port disposed one on each side of the said piston head. 75

7. A rotary engine of the character described including a rotatably mounted cylinder having outlet and inlet ports, an eccentrically mounted rotor disposed within the cylinder and touching at one point, said 80 rotor being formed with a transverse piston head recess and a circumferentially extending arm receiving recess, a radially movable piston head mounted in the first named recess, an arm carried thereby and disposed in 85 the second named recess and pivoted at its extremity to the rotor, the outer edge of the piston head being pivotally connected to the cylinder, said head being disposed between the outlet and inlet ports of the cylinder. 90

8. A rotary engine of the character described including a rotatably mounted cylinder, an eccentrically mounted rotor disposed within the cylinder, said rotor having a piston head receiving recess and a circumferentially extending arm receiving recess, a piston head disposed in the first named recess, an arm disposed in the second named recess and pivoted at its extremity to the rotor, said arm having its outer edge face curved 100 to the same degree as the curvature of the inner face of the cylinder, the outer edge of the head being pivotally connected to the cylinder and said cylinder being provided with an outlet and an inlet port disposed one 105 on each side of the head.

9. A rotary engine including a base, a casing mounted upon the base and including annular end walls and a peripheral wall, a cylinder mounted within the casing and including a peripheral wall spaced from the casing, and annular end walls having annular hubs extending through the end walls of the casing and rotatably mounted therein, a shaft passing through the casing and the cylinder and disposed eccentrically to the axis thereof, a rotor mounted on the shaft and located within the cylinder and touching at one point, said rotor having a transversely extending piston head recess and a circumferentially extending arm receiving recess, and a piston head mounted within the first named recess and having an arm projecting therefrom and disposed in the second named recess, the extremity of the arm being pivotally connected to the rotor and the outer edge of the piston being pivotally connected to the cylinder, the outer edge face of the arm having a curvature of the same degree as the curvature of 120 125 130

the inner face of the cylinder, said cylinder being formed with an inlet and an outlet port disposed one on each side of the piston head, the inlet port opening into the space 5 between the outer casing and the cylinder.

10. A rotary engine including a base, a casing mounted upon the base and including annular end walls and a peripheral wall, a cylinder mounted within the casing and including a peripheral wall spaced from the casing, and annular end walls having annular hubs extending through the end walls of the casing and rotatably mounted therein, a shaft passing through the casing and the cylinder and disposed eccentrically to the axis thereof, end plates mounted on the end walls of the casing and having inwardly extending hubs surrounding the shaft and rotatably supporting the hubs of the cylinder, a rotor mounted on the shaft and located within the cylinder and touching at one point, said rotor having a transversely extending piston head recess and a circumferentially extending arm receiving recess, 25 and a piston head mounted within the first named recess and having an arm projecting therefrom and disposed in the second named recess, the extremity of the arm being pivotally connected to the rotor and the outer edge of the piston being pivotally connected to the cylinder, the outer edge face of the arm having a curvature of the same degree as the curvature of the inner face of the cylinder, said cylinder being formed with 35 an inlet and an outlet port disposed one on each side of the piston head, the inlet port opening into the space between the outer casing and the cylinder.

11. A rotary engine including a base, a casing mounted upon the base and including annular end walls and a peripheral wall, a cylinder mounted within the casing and including a peripheral wall spaced from the casing, and annular end walls having annular hubs extending through the end walls of the casing and rotatably mounted therein, a shaft passing through the casing and the cylinder and disposed eccentrically to the axis thereof, a rotor mounted on the shaft and located within the cylinder and touching at one point, said rotor having a transversely extending piston head recess, and a circumferentially extending arm receiving recess, a piston head mounted within the first named recess and having an arm projecting therefrom and disposed in the second named recess, the extremity of the arm being pivotally connected to the rotor and the outer edge of the piston being pivotally connected to the cylinder, the outer edge face of the arm having a curvature of the same degree as the curvature of the inner face of the cylinder, said cylinder being formed with an inlet and an outlet port disposed one on each side of the piston 65

head, the inlet port opening into the space between the outer casing and the cylinder, packing disposed between the rotor and the cylinder, and packing disposed between the hub of the cylinder and the bearing in the outer casing. 70

12. A compound rotary engine including an outer casing, a cylinder rotatably mounted in the casing and having an inlet and an outlet port, a rotor eccentrically mounted within the cylinder and contacting at one edge with the cylinder, said rotor having a circumferentially extending partition receiving recess, an annular partition attached to the cylinder and extending into said recess, and thereby dividing the space within the casing into a high and a low pressure chamber, radially movable blades mounted upon the rotor, one on each side of the partition and urged into contact with the interior face of the casing, the rotor being pivotally connected to the cylinder and each of said blades being disposed between the inlet and outlet ports of the respective chambers, the outlet port from the high pressure chamber 80 opening into the space behind the blade of the low pressure chamber. 85

13. A compound rotary engine including an outer casing, a cylinder rotatably mounted in the casing and having an inlet and an outlet port, a rotor eccentrically mounted within the cylinder and contacting at one edge with the cylinder, being made in two sections, one of said sections having a hub contacting with the other section to thereby 95 provide an annular partition receiving recess, a partition mounted upon the cylinder and extending into said recess, said partition being formed with an outlet port and dividing the cylinder into a high pressure 100 and a low pressure chamber, radially movable blades mounted upon the rotor, one on each side of the partition and urged into contact with the interior face of the casing, the rotor being pivotally connected to 105 the cylinder and each of said blades being disposed between the inlet and outlet ports of the respective chambers, the outlet port from the high pressure chamber opening into the space behind the blade of the lower 110 pressure chamber. 115

14. A rotary engine including a casing having annular end walls and a peripheral wall, a cylinder mounted within the casing and including a peripheral wall spaced from the casing, and annular end walls having annular hubs extending through the end walls of the casing and rotatably mounted therein, a shaft passing through the casing and the cylinder and disposed eccentrically to the axis thereof, a rotor mounted on the shaft and located within the cylinder and touching the cylinder at one point, said rotor having a transversely extending piston head recess and a circumferentially 125 130

extending arm receiving recess, the extremity of the arm being pivotally connected to the rotor and the outer edge of the piston being pivotally connected to the cylinder, said cylinder being formed with an inlet port and an outlet port disposed on each side of the piston head, the outlet port opening into a circular space formed in the cylinder wall concentric to the hub thereof, 10 the adjacent annular hub of the adjacent

end wall of the casing having an exhaust port communicating at all times with said space.

In testimony whereof I affix my signature in presence of two witnesses.
